UNITED STATES PATENT OFFICE.

THEODORE BODDE, OF NIAGARA FALLS, NEW YORK.

METHOD OF AND APPARATUS FOR ELECTRICALLY PRODUCING SOUND.

Application filed July 5, 1924, Serial No. 724,379. Renewed January 7, 1927.

This invention relates to a method of and apparatus for electrically producing sound, and more particularly to a method of and apparatus for transforming sound waves or 5 impulses into corresponding current pulsations or impulses by the action of a magnetically controlled electron discharge device.

As is well known, the electron stream or 10 current between the electrodes of a vacuum tube or electron discharge device may be controlled by means of a magnetic field; and in the action of these magnetically controlled devices, if a constant voltage is impressed 15 between the cathode and anode, the current that flows through the tube, that is, the electron stream that discharges from the cathode and impinges on the anode, while unaffected by a magnetic field having a strength less 20 than a certain critical value, is reduced to zero if the magnetic field is increased beyond that value; and thus by changing the strength of the magnetic field to magnitudes below or above a critical amount, the electron stream 25 or current across the electrodes and hence the current in a working circuit connected to the electrodes may be respectively established or extinguished.

The magnetically controlled electron tube, 30 or magnetron as it is termed, in one of its most efficient forms comprises a vacuous vessel of cylindrical configuration provided with a linearly disposed filament which when heated to incandescence emits an electron 35 stream which impinges upon a cylindrical plate or anode symmetrically surrounding the cathode, the stream being controlled by means of a magnetic field which may be produced by an energized solenoid or coil surrounding the tube or vessel. The paths of 40 movement of the electrons projected from the cathode are found to be influenced by the magnetic field, the paths being bent or curved by the magnetic field; and the degree 45 of curvature imparted to the paths varies with the strength of the magnetic field. When the field is below a critical value, the electron paths although curved still intersect the cylindrical anode, and since the 50 electrons impinge on the anode, the current through the tube remains unaffected. When however the magnetic field exceeds the critical value, the electron paths are bent sufficiently to prevent the electrons from reaching 55 the anode, and since the electrons do not impinge thereon, no current flows across the

electrodes and the current in the working circuit connected to the electrodes is accordingly extinguished.

I have discovered, as is disclosed in my 60 copending application Ser. No. 613,273, filed Jan. 17, 1923, that this phenomenon or property of the magnetic control of the electron emission of the tube or device may be utilized for effecting the transformation of 65 sound vibrations or impulses into corresponding electrical impulses for sound production and transmission, and more particularly that when the controlling magnetic field is such as to produce an electron emission 70 which moves substantially tangentially to the anode, a relative vibration between the cathode and the anode electrodes in response to sound impulses will sensitively produce corresponding variations in the electron 75 stream impinging upon or touching the anode, and hence corresponding current variations in a working circuit connected to the anode and cathode.

In my copending application referred to, 80 I disclose a construction whereby vibration of the electron tube structure as a whole is made effective for producing the desired relative motion between the electrodes. I have found, however, that improved results 85 may be obtained by reducing the inertia of the parts set in motion by the sound impulses, and more particularly that by making the cathode the vibratable element, the device is rendered more sensitive to sound 90 impulses and any distortion of the reproduced sound is minimized. The provision of an improved method and electron discharge apparatus for transforming the sound impulses into electrical impulses in 95 which the substantially inertialess cathode is set into vibration in correspondence with the sound impulses is a prime desideratum of my present invention.

To the accomplishment of the foregoing 100 and such other objects as may hereinafter appear, my invention consists in the elements and their relation one to the other, as hereinafter particularly described and sought to be defined in the claims; reference 105 being had to the accompanying drawings which show a preferred embodiment of my invention, and in which:

Fig. 1 is a view showing my invention applied to a transmitter,

Fig. 2 is a view of a modification,

Fig. 3 is a graphical view showing the

electrical characteristics of the magnetron and the manner of adjusting the magnetic field thereof, and

5 Fig. 4 is a diagrammatic view depicting the principles or theory underlying the invention.

Referring now more in detail to the drawings and more particularly to Fig. 1 thereof, the magnetically controlled device or magnetron generally designated as M is shown to comprise the vacuous vessel or tube 10 provided with the cathode in the form of a straight or linear filament 11 arranged axially of the tube, and an anode 12, the said 10 anode comprising a section or portion of a surface of a cylinder as will be detailed further hereinafter arranged in circular symmetry with the cathode 11, the filament being provided with the sealed terminal 13 15 and the terminal 14 and the anode being provided with the sealed terminal 15; and encircling the tube 10 symmetrically with the cathode and anode there is provided the solenoid 16 for producing a controlling magnetic field.

For heating the filament to incandescence a closed circuit is provided which includes the battery 17, the opposite poles of which are connected to the filament terminals 18 30 and 14 by means of the conductors 18, 19, 20 and 21. As is well known, upon heating the filament 11 by means of this closed circuit, there will be an emission of electrons from the filament 11 to the anode 12, and 35 upon closing a working circuit connected to the anode and cathode a current will be established therethrough.

For energizing the solenoid 16, the same may be connected to a source of current 40 which may be the battery 17 by means of a circuit comprising the conductor 22, the coil of solenoid 16, conductor 23, rheostat 24 and conductor 19, the rheostat being employed for predetermining the degree of energization of the solenoid and hence the magnitude 45 of the magnetic field.

If the electron discharge device be subjected to a magnetic field normal or at right angles to the electron paths and below a predetermined amount, the emission of the electrons from the cathode and the impinging of these electrons on the anode of the device will be uninterrupted and unhindered, and if the tube be subjected to a 50 magnetic field beyond such predetermined amount, the electrons will be diverted and prevented from reaching the anode, resulting in an opening of the tube circuit and the opening of the working circuit controlled 55 thereby. The graphical representation of this phenomenon is shown in Fig. 3, in which the strength of the magnetic field is represented by the abscissæ, and the strength of the current flowing between the 60 cathode and anode is represented by the

ordinates of the graph. If the magnetizing influence is less than the line represented as CD, the current in the working circuit will be a maximum represented by the line XC. If, however, the magnetization passes the critical point D, the current in the working circuit decreases and rapidly diminishes to a minimum as the magnetic field approaches the value XE, the change along the curve DE being more or less abrupt as 70 the parts of the magnetron are more or less symmetrical in arrangement. Now if, instead of varying the magnetic field, the magnetic field is fixed at a value such that the electron stream moves substantially tangentially to the anode 12 and a relative vibration between the cathode 11 and anode 12 is produced, there will be obtained variations 75 in the electron stream reaching the anode, which variations are proportional in magnitude or amplitude and in frequency to the relative vibrations between the anode and cathode. By connecting across the electrodes a receiving or working circuit which may include a receiver 25, the conductor 26, the battery 27, conductor 28 connected to the anode 12, conductor 29 and conductor 21 connected to the cathode electrode 14, it will be apparent that the variations in the electron stream will produce corresponding 80 sound producing variations in the current of the working or receiving circuit.

That the change in the electric current or stream varies proportionally with the impressed mechanical vibrations of the cathode or filament will appear from a consideration of Fig. 4 of the drawings. In this figure I show in diagrammatic fashion the underlying theory of the invention, and I desire it to be understood that although this theory 90 is to be understood that although this theory 100 I believe to be properly explanatory of the phenomenon or the behaviour of the apparatus, the theory is presented by way of explanation only, and not by way of limitation. When the solenoid 16 is energized to 105 produce a magnetic field having a value at or about the critical value as represented for example by the asterisk (*) on the curve represented in Fig. 3, the current in the tube is 110 at the transition point, and the average electron path may be represented by the curve x (Fig. 4), the electron path being tangent to the anode 12. This, however, is only the 115 average path, and due to such factors as the physical dimension of the filament, the lack 120 of complete symmetry of the parts, etc., the electrons are projected from the cathode in a plurality of proximate paths such for example as the paths x, y and z, the electrons in the path z impinging on the anode, 125 and the electrons in the path y circling about in the closed path as shown, without touching the anode. When the cathode is vibrated, however, it will be evident that more or less of the electrons reach the anode ac- 130

cording to the position of the cathode with respect to the relatively stationary anode. Thus when the cathode occupies the position 11^a shown in Fig. 4, the electrons in all of 5 the paths will strike the anode 12 while when the cathode occupies the position 11^b, none of the electrons in the paths *x*, *y* and *z* will touch the anode. It will therefore be evident that the total electron stream emanating 10 from the filament and impinging against the cylindrical anode surface varies progressively with and in proportion to the vibratory motion that may be imparted to the filament 11.

15 For vibrating the substantially inertialess filament 11, the terminal 13 may be coiled as shown at 30, and the terminal 14 may comprise a short rigid metal rod which passes through the center of and is soldered 20 air-tight to a copper or phosphor bronze membrane 31, this membrane being sealed air-tight to the glass of the magnetron tube 10 at 32 in a manner well known to those skilled in the art. The membrane 31 is 25 preferably about one inch in diameter, and has a thickness of about 0.010 inches. With this construction it will be apparent that the rod terminal 14 forms a lever with its fulcrum at the membrane 31, so that the 30 rod-lever will be set into vibration when sound waves moving in the direction of the arrows shown in the figure impinge upon a disk or diaphragm 33 connected or fixed to the outer end of the rod 14. The vibratory 35 impulses produced at the outer end of the rod-lever will be reproduced in the inverse direction at the inner end of the rod, and will be transmitted to the filament 11, as will be obvious.

40 Referring now to Fig. 2 of the drawings. I show a modified form of magnetron construction in which longitudinal vibrations are imparted to the rod terminal in lieu of the transverse vibrations incident to the 45 structure shown in Fig. 1 of the drawings. In Fig. 2 the magnetron tube comprises an envelop or vessel 10' having the linearly arranged filament 11' and the symmetrically arranged cylindrical anode 12', one terminal 50 of the filament being sealed as at 13' and the other terminal comprising the rod 14' arranged substantially normal to the filament 11', the said rod being soldered air-tight to the membrane 31' which is arranged in a 55 plane parallel to the axis of the magnetron tube so that sound impulses impinging upon the diaphragm or disk 33' and moving in the direction as indicated by the arrow will produce longitudinal vibrations in the rod 60 14' and will correspondingly produce the desired movement of the filament 11' for varying the touching distance between the body of the electron stream and the anode 12'.

The anode 12 or 12' is a section or a part 65 of a cylinder, and more particularly a cylin-

der with one side cut away, and in the preferred form comprises a quadrant of a cylinder. The cylindrical anode, as distinguished from known magnetrons, is cut away on one side for the reason that if a full cylinder is 70 employed, any variation in the electron current on one side produced by the vibrations would be neutralized or compensated for by an equal and opposite variation on the opposite side, producing a net result of no variation in the working circuit. With one side of the anode, however, removed, the electron stream variations on one side of the cylinder produces the current in the working 75 circuit as desired.

80 The use and operation of the apparatus and the practice of the method will in the main be fully apparent from the above detailed description thereof. It will be further apparent that although I have shown 85 my invention applied to a transmitter wherein the filament is set directly into vibration in response to sound impulses, that this application of the invention has been given merely by way of example, and that other 90 applications will be obvious to those skilled in the art. For example, the magnetron may be subjected to vibrations of the mechanical vibrating system such as is employed in phonograph sound reproduction 95 for the transmission of speech. It will be further seen that with the provision of the apparatus described, an extremely sensitive transmitter is obtained, the moving element being substantially inertialess and the reproduced sound being free from unavoidable secondary current variations and 100 distortions.

105 While I have shown my device in the preferred forms, it will be apparent that many changes and modifications may be made in the structure disclosed without departing from the spirit of the invention, defined in the following claims.

I claim:

110 1. The method of transforming sound impulses into corresponding electrical impulses which consists in subjecting the electron stream of an electron discharge device to a magnetic field such that the electron stream 115 emanating from the cathode of the device is caused to move substantially tangentially to the anode of the device and in setting up vibrations of the cathode relatively to the anode responsive to sound impulses whereby 120 variations in the electron stream impinging upon or touching the anode are produced in correspondence with the sound impulses.

125 2. The method of transforming sound impulses into corresponding electrical impulses which consists in producing in an electron discharge device a curved electron stream moving from the cathode of the device to an electrode which is disposed substantially tangent to the electron stream and in set- 130

ting up vibrations of the cathode relatively to the anode responsive to sound impulses whereby variations in the electron stream impinging upon or touching the electrode are produced in correspondence with the sound impulses.

3. The method of transforming sound impulses into corresponding electrical impulses which consists in subjecting the electron stream moving from the cathode to the anode of an electron discharge device to a magnetic field which is normal to the paths of the electrons and which is of such magnitude as to cause the electron stream to move substantially tangentially to the anode and in setting up vibrations of the cathode relatively to the anode responsive to sound impulses whereby variations in the electron stream impinging upon or touching the anode are produced in correspondence with the sound impulses.

4. The method of transforming sound impulses into corresponding electrical impulses which consists in vibrating the cathode of an electron discharge device relatively to the anode in response to sound impulses to vary the condition of the electron stream emanating from the cathode and moving to the anode.

5. An apparatus for producing sound by variations of an electrical current comprising an electron discharge device having a cathode and an anode, means for causing the electron stream emanating from the cathode to move substantially tangentially to the anode and means for effecting a vibration of the cathode relatively to the anode responsive to sound impulses for producing variations in the electron stream impinging upon or touching the anode in correspondence with the sound impulses.

6. An apparatus for producing sound by variations of an electrical current comprising an electron discharge device having a cathode and an anode, means for curving the stream of electrons emanating from the cathode, the surface of the anode being arranged tangent to said stream, and means for vibrating the cathode for varying the touching distance between the body of the electron stream and the anode surface.

7. An apparatus for producing sound by variations of an electrical current comprising an electron discharge device having a cathode and an anode, means for producing a magnetic field effective for causing the electron stream emanating from the cathode to move substantially tangentially to the anode and means for effecting a vibration of the cathode relatively to the anode responsive to sound impulses for producing variations in the electron stream impinging upon or touching the anode in correspondence with the sound impulses.

8. An apparatus for producing sound by variations of an electrical current comprising an electron discharge device having a cathode and an anode, means for producing a magnetic field which is normal to the paths of the electrons emanating from the cathode and which is of such a magnitude as to cause the electron stream to move substantially tangentially to the anode and means for effecting a vibration of the cathode relatively to the anode responsive to sound impulses for producing variations in the electron stream impinging upon or touching the anode in correspondence with the sound impulses.

9. An apparatus for producing sound by variations of an electrical current comprising an electron discharge device having a cathode, an anode and a means producing an electron discharge controlling magnetic field which is at or about the critical point, and means for effecting a vibration of the cathode relatively to the anode to produce variations in the electron stream impinging on the anode.

10. An apparatus for producing sound by variations of an electrical current comprising an electron discharge device having a cathode and anode and means for vibrating the cathode relatively to the anode for varying the condition of the electron stream emanating from the cathode and moving to the anode.

Signed at Niagara Falls, in the county of Niagara and State of New York, this 30th day of June A. D. 1924.

THEODORE BODDE.
